Charles Turner Brown,
ATTORNEY

UNITED STATES PATENT OFFICE.

OTTO CULLMAN, OF CHICAGO, ILLINOIS.

AUTOMOBILE-HEATER.

1,009,052.

Specification of Letters Patent. Patented Nov. 21, 1911.

Application filed December 14, 1910. Serial No. 597,815.

To all whom it may concern:

Be it known that I, OTTO CULLMAN, a citizen of the United States, and a resident of Chicago, in the county of Cook and State of Illinois, have invented a new and useful Automobile-Heater, of which the following is a specification.

The principal objects of this invention are to obtain a radiator for automobiles which will use a portion of the exhaust from the motor for warming purposes, without interfering with the use of the muffler or cut-out, and which may be substituted for one or more of the boards which form the floor of the body of the automobile; and further to obtain a device which will be simple in construction, and durable and which will radiate heat therefrom only on the upper side thereof.

Additional objects sought by me are to obtain a radiator which is removable, and which provides an adjustment to control the quantity of exhaust mixture which is delivered thereinto.

A still further object is to obtain a device made and connected to the exhaust pipe of the motor in such manner as to permit more than one of said devices to be used in the same car body, and each one of said radiators to be used, independently of the others.

I attain these objects by the mechanism illustrated in the accompanying drawing, in which;

Figure 1 is a diagram of the chassis of an automobile provided with radiators embodying this invention installed in the floor thereof. Fig. 2 is a vertical section on line 2-2 of Fig. 3, viewed in the direction indicated by the arrows. Fig. 3 is a top plan view of a radiator embodying this invention. Fig. 4 is a vertical section on line 4-4 of Fig. 3, viewed in the direction indicated by the arrows. Fig. 5 is a vertical section, on an enlarged scale, on line 5-5 of Fig. 3, viewed in the direction indicated by the arrows. Fig. 6 is a side elevation of a short section of the exhaust pipe of a motor including the constructions by means of which my device is attached thereto, and of the muffler cut out.

Similar letters refer to similar parts throughout the several views.

A, Fig. 1, is the frame of an automobile chassis.

B is a portion of the exhaust pipe of a motor.

C is a pipe extending downward from pipe B and in communication therewith at its upper end.

D is a valve which seats to close the lower end of pipe C.

d is the valve stem of valve D, d' is a button on the upper end of stem d, and d'' is a spring on stem d yieldingly holding valve D seated.

E, E', E'', are respectively pipes or conduits communicating at one end with pipe C and at the other end with the inlet pipes of the radiators, (said radiators are marked 1, 2, and 3, in Fig. 1).

F is a frame forming an element of a radiator embodying this invention. I have heretofore made frame F of wood.

f, f, are broken lines in Fig. 3, indicating the mitered ends of the side and end pieces of the frame F.

G is the bottom plate and G' is the top plate of the radiator.

H is a sheet of asbestos or other heat insulating material which is laid or spread over the frame F and bottom plate G. The edges of sheet H are interposed between frame F and plate G'.

I, I, are strips of metal which are laid on the heat insulating material H and extend from one side of the device to the other.

I', I', are strips similar to strips I which extend from side to side of the radiators. The ends of strips I' are shown as resting on and embedded in heat insulating material H.

J, J, are supports placed between strips I, and I'.

K are bolts extending through the plate G', strips I', supports J, strips I, heat insulating material H and plate G; and k are nuts on bolts K, by means of which the several parts last above named are rigidly secured together.

To obtain a construction which permits the use of the radiator as a bottom board in the floor of an automobile car body, I make the plates G, G', of thin sheet metal securing them to the frame F by screws L and securing said plates together by means of the above described construction which includes strips I, I', supports J, bolts K and nuts k, to obtain what I term a truss which extends from side to side of the radiator.

A suitable number of these trusses are placed in the radiator (two are shown in Fig. 3), so

that the radiator may be walked on or otherwise used in the same manner and for the same purposes that the floor of an automobile car body is used.

5 To control the quantity of exhaust mixture delivered to the radiator embodying my invention and to permit the removal of the radiator at any time I have devised the construction particularly illustrated in Fig. 2
10 of the drawing, where the upper end of pipe E terminates in the flared mouth M into which the tube m (which tube I make of asbestos pipe), is forced when the radiator is in place. The pipe or conduit E and the flared end M thereof, are secured in the chassis of the automobile and are not readily removed, while the flexible tube m is removable from said end M.

20 N is a tube or pipe secured in the bottom of the radiator with its lower end inserted in flexible tube m. Tube or pipe N is the inlet to the radiator and O is the outlet.

25 P is a valve which seats to close the upper end of the pipe N.

30 p is the stem of valve P. Stem p is provided with screw threads and with the head p'.

35 Q is a spring mounted on stem p. By turning the head p' in one direction valve P is raised or opened from its seat and by turning it in the other direction the valve is seated and the function of the spring Q is simply to prevent the position of the valve becoming changed from the jars incident to the movements of the automobile.

40 The distance of the valve P from its seat determines the quantity of the heated products from the exhaust pipe which enter the radiator, and in practice a different quantity of such products is delivered to each one of the radiators in the floor.

45 One of the functions of the strips I, I', is to strengthen the plates G, G', and where said plates are made sufficiently thick said strips I, I', may be omitted from the construction of the device. In addition to the function above set forth these strips serve as washers at the ends of the supports J.

I claim;—

50 1. The combination of a frame, plates attached to the top and bottom of the frame, heat insulating material on the lower plate and on the frame, strips extending from one side of the frame to the other side, beneath the top plate and upon the heat insulating material, supports interposed between the strips and means to hold the plates and strips rigidly to said supports, all arranged
55 the top plate and upon the heat insulating material, supports interposed between the strips and means to hold the plates and strips rigidly to said supports, all arranged

to obtain a chamber between the heat insulating material and the upper plate, and said chamber provided with an inlet and an outlet.

2. The combination of a frame, plates attached to the top and bottom of the frame, heat insulating material on the lower plate and on the frame, strips extending from one side of the frame to the other side, beneath the top plate and upon the heat insulating material, supports interposed between the strips and means to hold the plates and strips rigidly to said supports, all arranged to obtain a chamber between the heat insulating material and the upper plate, and said chamber provided with an inlet and an outlet, a valve arranged to seat to close the inlet, means to move the valve from its seat, and means to yieldingly hold the valve in an adjusted position.

3. The combination of a frame, plates attached to the top and bottom of the frame, heat insulating material on the lower plate and on the frame, said frame and plates arranged to obtain a chamber between the heat insulating material and the upper plate, strips extending from one side of the frame to the other side, and resting on the sides of the frame and upon the heat insulating material, supports in said chamber between the upper plate and the strips, and means to hold said plates and strips to said supports and to force the strips down onto the insulating material to maintain said insulating material in place, said chamber provided with an inlet and with an outlet.

4. The combination of a frame, plates attached to the top and bottom of the frame, heat insulating material on the lower plate and on the frame, strips extending from one side of the frame to the other side beneath the top plate and upon the heat insulating material, supports interposed between the strips and means to hold the plates and strips rigidly to said supports, all arranged to obtain a chamber between the heat insulating material and the upper plate, and said chamber provided with an inlet and an outlet, a valve arranged to seat to close the inlet, means to move the valve from its seat, a flexible pipe joined to the bottom plate of the radiator and a stationary flaring pipe arranged to receive said flexible pipe when the radiator is placed thereover.

OTTO CULLMAN.

In the presence of—

CHARLES TURNER BROWN,
CORA A. ADAMS.
